UNITED STATES PATENT OFFICE.

CORNELIUS F. RUMELY, OF DETROIT, MICHIGAN, ASSIGNOR TO EVANS AUTO LOADING CO. INC., OF DETROIT, MICHIGAN.

HEADBLOCK STRAP.

Application filed February 4, 1928. Serial No. 251,936.

This invention relates to decks for supporting automobiles in freight cars and the like for the purpose of shipment, and has more particular reference to an improved 5 head block strap for use in anchoring or holding the wheel hub of the automobile in the head block of such a deck.

The method of anchoring or holding the wheel hub into the head block of a deck has 10 been to nail a comparatively long straight strap over the hub and to the head block of the deck after the automobile wheel hub has been placed in the head block. With this 15 method of fastening the hub in place after the automobile has been placed on the deck, it has been found difficult in many instances to obtain sufficient tension in the holding 20 strap to assure complete elimination of movement of the hub in the head block of the deck. It has also been found that, due to the length of strap necessarily used, there 25 is a tendency for the strap to stretch or become loosened even though it might have been tight on first application.

The primary object of the present invention, therefore, is to provide an improved head block strap by means of which the above objections are overcome.

A more specific object of the invention is 30 to provide an improved head block strap which may be readily applied so as to insure complete elimination of movement of the hub in the head block, and which, when once applied, will not stretch or become 35 loosened.

A further object is to provide a head block strap of the above kind which may be economically manufactured, by means of which a firm purchase may be had upon the wheel 40 hub, and which will present no objectionable inwardly projecting parts capable of interfering with proper seating of the wheel hub in the head block of the deck.

Other objects will appear as the nature of 45 the invention is better understood, and the same consists in the novel form, combination and arrangement of parts hereinafter more fully described, shown in the accompanying drawing and claimed.

In the drawing:

Figure 1 is a fragmentary transverse section of a freight car, showing one of a plurality of decks used to support an automobile in an elevated position within the 50 car, the deck being equipped with a head

block strap embodying the present invention;

Figure 2 is an enlarged fragmentary vertical section on line 2—2 of Figure 1;

Figure 3 is a vertical section on line 3—3 60 of Figure 2; and

Figure 4 is a diagrammatic plan view illustrating the blank from which the present head block strap is formed, as well as showing the manner in which a plurality of the 65 blanks may be conveniently stamped from a sheet of metal.

Referring more in detail to the drawing, 5 indicates the freight car having a floor 6 and side walls 7, and within which the automobile 8 is supported in an elevated position for shipment by means of a plurality of decks, one of which is shown at 9. The decks may be of any well known or preferred construction, but as shown, consists 70 of a pair of supporting legs 10 arranged in upwardly converging relation and having their upper ends rigidly secured together and in engagement with one another by suitable means including a head block 11 formed in 75 its upper edge with a circular seat or notch 12 for snug seating reception of the shipping hub cap 13 used on the hub 14 of the automobile wheel 15. It will of course be understood that the buck is arranged in an upwardly and inwardly inclined position as 80 shown in Figure 1, in which position it is securely held by means of a brace 16 interposed between the side wall 7 of the car and the upper end of the deck. The upper portion 85 of the inner surface of the head block 11 is usually beveled as at 17 so that this beveled surface portion is vertically disposed when the deck is secured in its laterally inclined position of Figure 1, thereby 90 enabling proper seating of the shipping hub cap 13 in the seat 12.

The present invention aims to provide an improved device or strap adapted to be placed over the shipping hub cap 13 and fastened to the head block 11 for firmly anchoring or holding the wheel hub or shipping hub cap in the seat 12 of the head block. As shown, this strap is formed from a blank stamped from a sheet of metal in the shape shown in Figure 1 and consisting of a strip having aligned end portions 18 and an integral central connecting portion 19 offset laterally in the plane of the strip to one side of the end portions 18. The central 105 110

or intermediate portion 19 is offset laterally with respect to the end portions 18 substantially a distance equal to the width of the strip so as to define longitudinally aligned 5 lines of connection 20 between the adjacent ends of the portions 18 and 19 coincident with the adjacent longitudinal edges of the portions 18 and 19. Suitable openings 21 are provided in the end portions 18 to permit 10 the passage of nails and the like so as to facilitate fastening of the strap to the head block as and in a manner that will presently become apparent.

In forming the present anchoring device 15 or strap from this blank, the end portions 18 are bent at right angles to the central or intermediate portion 19 on the lines 20. The central portion 19 is then formed into circular shape to conform to the shape of the 20 shipping hub cap 13 used on the automobile hub 14, substantially as shown in Figures 2 and 3.

In applying the head block strap the intermediate portion 19 is disposed to project 25 outwardly as shown in Figure 3, and the end portions 18 are flatly engaged with the inner face of the head block and secured in such position by means of nails passed through the openings 21 and driven into the 30 head block as shown clearly in Figure 2. As the intermediate portion 19 projects outwardly so as to overlie the seat 12, a firm purchase will be had upon the shipping hub cap, and better engagement of the hub cap 35 in the seat 12 is provided than would be the case were the portion 19 to project inwardly from the end portions 18, or inwardly relative to the latter. It will be noted that the central portion 19 of the strap and the notch 40 or seat 12 of the head block 11 jointly form a circular opening of a size to snugly admit the shipping hub cap of the automobile and insure complete elimination of movement of the hub in the deck head.

An advantage of the present head block 45 strap is that it may be placed in position and nailed during the assembly of the deck, thereby assuring proper location and uniform application. Further, the strap embodies a central portion which conforms to 50 the shipping hub cap, thereby assuring a snug fit. Still further, the total length of the strap, and more particularly the distance from the ends of the contacting portion 55 19 to the nailing locations is less than

that of the usual old style of strap, thereby lessening the possibility of stretching or loosening of the strap while the car is in transit.

It will be noted that the design of the 60 blank as shown in Figure 4 is such as to permit economical manufacture, inasmuch as the intermediate portions 19 are so located as to allow progressive blanking transversely of a sheet of metal of given width, thereby 65 eliminating material waste in manufacture.

From the above description it is believed that the construction, manner of use and advantages of the present invention will be readily apparent to those skilled in the art. 70

Minor changes may be made without departing from the spirit and scope of the invention as claimed.

What I claim as new is:—

1. A head block strap for automobile 75 shipping decks comprising a metal strip having end portions adapted to flatly engage and be secured to the inner face of the head block, and an intermediate portion disposed at right angles to the end portions and curved to substantially conform to a wheel hub, the sides of the opposite ends of said intermediate portion being joined to adjacent side edges of the upper ends of said 80 end portions. 85

2. A head block strap for automobile 90 shipping decks formed from a metal strip having longitudinally alined end portions connected by an intermediate portion offset laterally of said end portions in the plane 95 of the strip, said end portions being adapted to be bent at right angles to said intermediate portion, and said intermediate portion being adapted to be curved to substantially conform to a wheel hub. 95

3. The combination with the head block 100 of an automobile shipping deck having a circular seat in its upper edge to snugly receive the lower portion of a wheel hub, of a strap for securing the hub in said seat embodying end portions flatly fastened to the inner face of the head block, and an intermediate portion curved to snugly fit over the upper portion of the wheel hub and disposed at right angles to said end portions, said intermediate portion projecting laterally outwardly of said end portions to overlie 105 said seat of the head block.

In testimony whereof I affix my signature.

CORNELIUS F. RUMELY.
